UNITED STATES PATENT OFFICE

161,454

HOUSEHOLD MIXER

Alfonso Iannelli, Park Ridge, Ill., assignor to John Oster Manufacturing Company, Racine, Wis., a corporation of Wisconsin

Application January 22, 1949, Serial No. 405

Term of patent 14 years

(Cl. D44—1)

To all whom it may concern:

Be it known, that I, Alfonso Iannelli, a citizen of the United States residing at Park Ridge, in the county of Cook and State of Illinois, have invented a new, original, and ornamental Design for Household Mixer, of which the following is a specification, reference being had to the accompanying drawing, forming part thereof.

Figures 3 and 4 are views of the opposite ends of the mixer.

The outline of a pair of agitators shown in broken lines in Figure 1 is for illustrative purposes only.

I claim:

The ornamental design for a household mixer, as shown and described.

ALFONSO IANNELLI.
